COMBINATION AIR FILTERING AND COLLECTING UNIT FOR TEXTILE WASTE PRODUCTS

R. Hovan Hocutt and Thomas E. Mullinax, Charlotte, N.C., assignors to Pneumafil Corporation, Charlotte, N.C., a corporation of Delaware

Filed Aug. 27, 1965, Ser. No. 87,198

Term of patent 14 years

(Cl. D9—2)

FIG. 1.

FIG. 2.

FIG. 1 is a front perspective view of a combination air filtering and collecting unit for textile waste products embodying our new design;

FIG. 2 is a rear perspective view thereof.

This application is a division of copending application S.N. D78,632, filed February 14, 1964, now Patent Design 203,155.

What we claim is:

The ornamental design for a combination air filtering and collecting unit for textile waste products, as shown.
